UNITED STATES PATENT OFFICE.

GEORGE HORNECKER, OF ELMHURST, NEW YORK, ASSIGNOR, BY MESNE ASSIGNMENTS, TO CONWELL GRAPHIC COMPANY, INCORPORATED, OF NEW YORK, N. Y., A CORPORATION OF NEW YORK.

ADVERTISING DEVICE.

Application filed July 21, 1924. Serial No. 727,156.

This invention relates to advertising devices, and with regard to certain more specific features, to a representation of a rectilinear object, and a display support therefor.

Among the several objects of the invention may be noted the provision of a simple and inexpensive device for displaying a likeness of a rectilinear object together with suitable legends; and the provision of a strikingly attractive device of this type which can be made from a single blank and shipped flat. Other objects will be in part obvious, and in part pointed out herein-after.

The invention accordingly comprises the features of construction, combinations of elements, and arrangements of parts, which are exemplified in the constructions hereinafter described and the scope of the application of which will be indicated in the following claims.

In the accompanying drawings, in which are shown two of various possible embodiments of this invention,

Fig. 1 is a plan view of the developed blank after die-cutting and printing;

Fig. 2 is a front elevation of the device assembled for display purposes;

Fig. 3 is a side elevation of Fig. 2;

Fig. 4 is a top plan view of Fig. 2;

Fig. 5 is a plan view showing the device folded preparatory to shipping;

Fig. 6 is an edge view of Fig. 5 from the front;

Fig. 7 is a plan view of the developed blank of a modification of the device; and

Fig. 8 is an assembled side elevation of the modification shown in Fig. 7.

Similar reference characters indicate corresponding parts throughout the several views of the drawings.

Referring now more particularly to Figs. 1 to 4 of the accompanying drawings there is illustrated at 1 a device formed of a single sheet of suitable material such as patent coated solid manilla. For a size such as 18½ x 44 inches a thickness of 25 points is suitable.

The device may take a variety of forms but in the present embodiment its salient characteristic is its likeness, in part, to a rectilinear box or carton 3, usually higher than its width and wider than its thickness,

standing in relief, carrying suitable legends 55 and the like (not shown) and having as a background slidewardly disposed wings 5 and 7 and an upwardly disposed wing 10. The box-like portion 3 is disposed at an angle to the vertical wings 5 and 7 when 60 assembled for display.

In making the device shown in Fig. 1, only two operations are required, namely, lithographing or the equivalent and die cutting. The dotted lines 9, 11, 13, 15, 17 and 19 indicate scoring to facilitate bending of the device from the flat or shipping form shown, in Figs. 1, 5 and 6, to a display form, shown in Figs. 2, 3 and 4. The double lines 21, 23, 25, 27, 29 and 31 indicate incisions 70 whose uses will be explained.

Part of the support rests upon the floor or showcase or the like, in a plane in advance of the other parts of the base. This fact, coupled with the fact that the device 75 is of one piece, with scoring converging toward the top to make the device stable, ensures the stability and rigidity necessary for display purposes, when substantially thinner material is used than is ordinarily 80 used for devices of similar size.

In the preferred construction there are six score lines 9, 11, 13, 15, 17 and 19, which divide the article into seven parts 10, 33, 5, 35, 37, 39 and 7. The pairs of form 85 score lines 9, 13, 11 and 15 each have their respective lines converge toward the top of the article. The two lines, 13 and 15 are completed at their lower ends by incisions 29 and 31. These last named score lines 13 and 90 15 together with the incisions 29 and 31 and the lateral score 17 bound what later appears to an observer as the box 3 front section and a base 41 upon which said box 3 rests. The incisions 29 and 31 are jogged 95 so as to include in the box-front-and-base plane 37 the small lateral areas 43 and 45 for ornamental purposes giving the base and box a stable appearance.

The dividing line 47 (lithographed) between box and base extends to the right and left into the intermediate sections 35 and 39 where it continues to define the box in illustration. Within the sections 35 and 39 the line 47 turns upwardly at right angles 100 at its ends, forming the lines 49 and 51 which serve to bound the rear of the box 105 illustration when in display position. The

sections 35 and 39 are adapted by means of scores 13 and 15 to bend rearwardly through 90 degrees.

After the sections 35 and 39 have been bent to a 90 degree-rearward position, the extreme side sections or wings 5 and 7 are bent forwardly through an angle adapted for best display, which is usually 90 degrees. We now have the front, sides and base of the depicted box in position, as also the side wings for background and display purposes.

The front of the depicted box slants rearwardly toward its top as does the base portion 41, the side portions or wings 5 and 7 are vertical and the intermediate sections 35 and 39 act as connecting links by virtue of the scores 9 and 13 and 11 and 15 and their convergence.

The top of the box is completed by first folding through 90 degrees, on the score 17, the sections 53 and 55 of the top section or upper intermediate portion 33. The sections 53, 55 form closing sections for the purpose of closing openings left by ears 67. The central portion 54 of section 33 may now be bent backward through 90 degrees on the score 17 and the top wing 10 forward through 90 degrees on the score 19 and the incision slots 57 and 59 registered with the incision slots so that the closing sections 53 and 55 lie in under the central part 54 of intermediate portion 33, thereby closing the openings 61 and 63 left by the incisions 25 and 27 and folding of the wing 10. (Fig. 4.) This gives the depicted box top a solid appearance.

By having the top and front of the depicted box 3 stand out and slant as has been described, while the rearward and bottom lines of the same are printed with the background, a pleasing sense of relief is obtained at once with a blending of the depicted box with the subject material of said background, thereby giving a more desirable effect than could otherwise be obtained.

It will be seen that no extraneous supports are required, and no gluing or expensive folding is required either in manufacture or installation of the article.

In the present adaptation, the slots 21 and 23 are cut along the box outlines 49 and 51 thereby causing the upper display wing 10 to assume a position parallel to the box slant. The slots 21 and 23 may be cut in other positions bringing about different results.

In Fig. 7 the slots 21 and 23 are cut along the scores 9 and 11 causing the wing 10 to assume a position which is vertical, parallel to, and substantially in the plane of the side wings 5 and 7, when said wings are bent as far forward as possible. In the latter position the ears 65 and 67 act as guides to parallel relationship between the wings. Any

angle between the two illustrated ones may be obtained with the wing 10 by properly cutting the slots 21 and 23 intermediately between the positions shown.

It will thus be seen that the wing 10 may either brace the side portions 5 and 7 and lie substantially in their planes, or be entirely forward of said portions at some desired angle.

The side portions 5 and 7 and the upper wing 10 may take a variety of shapes at their outward extremities. The purpose of the upper wing 10 is to raise the optical center of the device thereby avoiding a squat appearance and to increase the display area. The side portions 5 and 7 increase the display area and provide a background.

The shipping arrangement of the device is shown in Figs. 5 and 6 where the top wing 10 and the upper section 33 are kept in one plane and folded forward on the central section 37 by means of the score 17. The side sections 5 and 7 are then folded backwards consecutively by means of scores 9 and 11. A flat shipping package may thus be obtained.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. An advertising device comprising a single sheet having certain score lines thereon adapted to divide said sheet into a front section, intermediate sections and side wings; other score lines arranged laterally with respect to said first-named score lines together with incisions adapted to divide closing sections from said intermediate sections, an upper intermediate portion formed from said front section and an upper display wing above said upper portion; ears on said upper display wing cut from said upper intermediate portion and said closing sections; whereby said front section may be folded to stand in relief with respect to said side and upper wings, the said intermediate sections and upper intermediate portion being arranged angularly to close the said closing sections, the front section and intermediate sections and upper intermediate portion taking relative positions so as to simulate a container, said closing sections lying under the opening left in the upper section where said ears were cut out; and incisions in said ears adapted to engage other incisions to lock the device in erected position.

2. An advertising device comprising a sin-

gle sheet having four score lines across it adapted to divide said sheet into a front section, side wings, and intermediate joining sections; a pair of laterally arranged 5 score lines adapted with incisions to divide hinged closing sections from said intermediate joining sections, an upper intermediate portion above said front section, and an upper display wing above said upper 10 intermediate portion; means for interlocking the upper display wing with said side wings

and joining sections, said closing sections being adapted to be folded in under said upper intermediate portion when the device is folded to interlock the display wing, the 15 front section and intermediate sections and upper intermediate portion taking relative positions so as to simulate a container.

In testimony whereof, I have signed my name to this specification this 14th day of 20 July, 1924.

GEO. HORNECKER.
